UNITED STATES PATENT OFFICE

THOMAS MAYERHOFER, OF CHICAGO, ILLINOIS, ASSIGNOR TO CHARLES TUTEUR, OF CHICAGO, ILLINOIS

DESIGN FOR A LAWN SPRINKLER

Application filed January 30, 1921. Serial No. 38,495. Term of patent 7 years.

To all whom it may concern:

Be it known that I, THOMAS MAYERHOFER, a citizen of the Republic of Germany, and resident of Chicago, in the county of Cook and State of Illinois, have invented a new, original, and ornamental Design for a Lawn Sprinkler, of which the following is a specification, reference being had to the accompanying drawing, forming a part thereof.

The figure is a view in perspective of a lawn sprinkler showing my new design.

I claim:

The ornamental design for a lawn sprinkler substantially as shown.

Signed at Chicago, in the county of Cook, and State of Illinois, this 26th day of January, A. D. 1931.

THOMAS MAYERHOFER.
